UNITED STATES PATENT OFFICE.

JOHN E. HAMILTON, OF SMITHTON, PENNSYLVANIA.

TOOTH-BRUSH.

1,179,426.

Specification of Letters Patent.

Patented Apr. 18, 1916.

Application filed July 23, 1913. Serial No. 780,782.

To all whom it may concern:

Be it known that I, JOHN E. HAMILTON, citizen of the United States, residing at Smithton, in the county of Westmoreland and State of Pennsylvania, have invented 5 certain new and useful Improvements in Tooth-Brushes, of which the following is a specification.

This invention relates to improvements in 10 tooth brushes and more particularly to the bristles thereof.

The primary object of the invention contemplates the provision of specially shaped 15 bristles adapted to be arranged or embedded within the head of the brush handle in such a novel and peculiar manner as to render the action thereof upon the gums and teeth of a person less painful than the bristles now employed.

20 A further object of the invention contemplates the provision of a plurality of curved end bristles arranged in series disposed to extend longitudinally of the brush head and transversely thereof, one bristle of 25 each series alternating with the bristles of the adjacent series thereby increasing the cleaning properties of the tooth brush.

The invention still further resides in the 30 provision of bristles of the ordinary type having the curved end bristles disposed to surround or inclose the same thereby deriving the advantages and benefits produced by both forms of bristles.

35 The above and additional objects are accomplished by such means as are illustrated in their preferred embodiment in the accompanying drawings, described in the following specification and then more particularly pointed out in the claims which are appended hereto and form a part of this application.

40 In describing my invention in detail reference will be had to the accompanying drawings wherein like characters denote like 45 or corresponding parts throughout the several views, and in which:—

Figure 1 is a front elevation of a tooth brush constructed in accordance with my invention; Fig. 2 is a similar view showing the 50 arrangement of the curved bristles when employed in connection with the straight bristles now commonly used; and Fig. 3 is an enlarged detail perspective view illustrating the manner in which the bristles are 55 embedded within the head of the brush.

Referring now to the drawings wherein

is illustrated the preferred embodiment of my invention the numeral 1 designates a brush handle of ordinary construction having the usual opening 2 formed in one end 60 thereof to facilitate the suspension of the brush when not in use. A head 3 is formed integrally with the handle 1 at the opposite end thereof from that of the opening 2, the head having specially formed bristles 65 embedded therein as illustrated to advantage in Fig. 3 of the drawings.

The bristles, designated by the numeral 4 are arranged in series, one series extending longitudinally of the brush head 3 and another series extending transversely of the 70 said head, the bristles 4 of the one set being disposed transversely of the bristles 5 of the said other set thereby increasing the cleaning properties of the brush when in practical use. 75

Upon reference to Fig. 3 of the drawings, it will be seen that each bristle is formed from a single hair or other material bent as illustrated after the fashion of an inverted U with the free ends embedded in the head of the brush, the curved or connecting portion of each bristle forming the engaging surface of the bristle during the use or application of the invention. The said 80 curved portion of the bristles renders the scratching and injury to the gums less painful without decreasing the cleaning properties of the brush. 85

In Fig. 2 I have shown the curved or 90 double bristles surrounding a plurality of single stem bristles 6, the former acting as a guard or protection against the injury to the gums that would otherwise occur were the said curved bristles not provided. The 95 curved bristles in this instance are also disposed alternately, that is one bristle extending transversely of the brush head and the next or adjacent bristle extending longitudinally thereof. 100

It will be seen from the above, taken in connection with the accompanying drawings that by disposing or arranging the bristles in the above described manner the cavities in the teeth may be easily reached and that 105 the pointed or sharpened ends of the bristles are not brought directly into engagement with the gums; and that the curving of the bristles as illustrated renders the fastening thereof more secure as both ends of the 110 bristle are embedded in the head 3 of the brush and not one end as heretofore.

It will be understood that the above description and accompanying drawings comprehend only the general and preferred embodiment of my invention and that various minor changes in details of construction, proportion and arrangement of parts may be made within the scope of the appended claims and without sacrificing any of the advantages of my invention.

Having thus fully described my invention, what I claim as new and desire to secure by Letters Patent, is:—

1. A tooth brush including a head portion, bristles having their ends embedded within the said head, the said bristles being bent intermediate their ends to form curved engaging surfaces, the said bristles being arranged in series, certain of which extend transversely of the brush head and

the others of which extend longitudinally 20 thereof.

2. A tooth brush including a head portion, bristles secured to the said head portion, the said bristles being bent intermediate their ends, the ends of each bristle being 25 embedded within the said head, the said bristles being arranged in series upon the said head, certain of which extend transversely thereof, the others of which extend longitudinally thereof, thereby alternating 30 the position of the bristles throughout the entire cleaning surface of the brush.

In testimony whereof I affix my signature in presence of two witnesses.

JOHN E. HAMILTON.
